UNITED STATES PATENT OFFICE.

JOHN P. McDONALD, OF ORANGE, TEXAS.

INTERLINER FOR TIRES.

1,318,095.

Specification of Letters Patent.

Patented Oct. 7, 1919.

Application filed September 20, 1918. Serial No. 254,933.

To all whom it may concern:

Be it known that I, JOHN P. McDONALD, a citizen of the United States, residing at Orange, in the county of Orange and State 5 of Texas, have invented a new and useful Interliner for Tires, of which the following is a specification.

The subject of this invention is an interliner for tires adapted to be used on pneumatic tires.

The main object of the invention is the provision of an interliner which will properly adjust itself to the inner walls of the outer casing.

Another object of the invention is the provision of an interliner which will adjust itself to the size of the inner tube.

Another object of the invention is the provision of an interliner which will lock under pressure of the inner tube.

The invention also contemplates generally improving the construction and enhancing the utility of interliners.

With the foregoing and other objects in view, which will appear as the description proceeds, the invention resides in the combination and arrangement of parts and in the details of construction hereinafter described and claimed, it being understood that changes 25 in the precise embodiment of the invention herein disclosed can be made within the scope of what is claimed without departing from the spirit of the invention.

A practical embodiment of the invention 35 is shown in the accompanying drawing, wherein:

Figure 1 is a cross section of a tire equipped with an interliner constructed in accordance with the invention;

Fig. 2 is a plan view of one of the fastening devices;

Fig. 3 is a side elevation of a modified form of fastener;

Fig. 4 is a plan view of the same;

Fig. 5 is a fragmentary view in side elevation of a further modification of the fastener;

Fig. 6 is a plan view of the same;

Referring to the drawing by numerals of 50 reference:

The usual inner tube of a pneumatic tire is indicated by the numeral 1, and the outer casing by the numeral 2, while the rim on

which the tire is secured is indicated by the numeral 3.

55

Between the inner tube 1 and the outer casing 2 is placed the interliner 4 which forms the subject of the present invention. The interliner 4 is made of any suitable flexible material, the same being, preferably, 60 non-elastic. The interliner 4 encircles the inner tube and has its longitudinal edges lapping, as at 5.

Suitably spaced along the longitudinal edge of the inner lap, are tacks having large 65 flat heads 6, from which extend the blunt pointed spurs 6'. The spurs 6' extend through the inner lap and for a suitable distance beyond the outer surface thereof, and are adapted to be pressed into the outer lap 70 of the interliner to bind the lapping portions together and lock the liner against further expansion. This locking is caused by the pressure of the inner tube when the same has been inflated to a sufficient extent to 75 properly fill the casing.

In place of the spaced tacks just described, short plates 7 may be used, from which plates are struck the spaced spurs 8, which are somewhat blunted and which pass 80 through the inner lap of the interliner and are forced into the outer lap, as heretofore described, to lock the interliner against further expansion.

A further modification of the locking 85 means consists in an elongated plate 9, which may extend along the longitudinal edge of the interliner for the complete length of the interliner, and which plate has spurs 10 struck downwardly therefrom for the purpose heretofore set forth.

The operation is as follows:—The interliner is placed about the inner tube and inserted in the casing. The inner tube is then inflated, the interliner gradually expanding, 95 until the inner tube has received a proper pressure of air. The pressure will then cause the blunt spurs to pierce the outer lap of the interliner and lock the interliner against further expansion. This will prevent undue strain on the outer casing, and will also insure against pinching the inner tube, and thereby injuring the same.

Having thus described the invention, what is claimed as new and sought by Letters 105 Patent, is:

An interliner for tires, including a strip of flexible material having overlapping edges, an elongated plate having spurs, engaging one edge of the interliner throughout its length, said spurs adapted to extend through the overlapping edges, of the interliner for holding the same in position.

In testimony that I claim the foregoing as my own, I have hereto affixed my signature in the presence of two witnesses.

JOHN P. McDONALD.
